[57] ABSTRACT

Underground stowing or packing apparatus for stowing or packing debris into a pack-hole or worked out mineral seam comprising, when the apparatus is operationally associated with the pack-hole or seam, one or more chains adapted to extend over the length of the pack-hole or seam required to be stowed or packed with debris and into or beyond a mine roadway adjacent to said pack-hole or seam, the chain or chains each having an upper and lower run passing at their ends about a drive sprocket and a return sprocket respectively and only being guided and supported at their ends, a sweeping means mounted on the chain or chains so as to be located at or near the roof of the pack-hole or worked out seam and so as to be traversable by the chain or chains between a debris collecting position and a debris packing or stowing position, means to anchor the drive and return sprockets so as to tension the chain or chains therebetween and means for constraining the movement of debris away from a pack as it is being formed in the pack-hole or worked out mineral seam.

STOWING AND PACKING DEBRIS IN MINES

This invention relates to an apparatus for stowing debris or for building packs of debris on one or both sides of a mine roadway to assist in supporting the roof above and adjacent the roadway, or for filling worked out seams of mineral.

The present invention provides apparatus by which the building of packs is commenced at the roadway side of each pack, working away from the roadway and also which enables the packing to be mechanically effected right up to the roof.

According to the present invention, underground stowing or packing apparatus for stowing or packing debris into a pack-hole or worked out mineral seam comprises, when the apparatus is operationally associated with the pack-hole or seam, one or more chains adapted to extend over the length of the pack-hole or seam required to be stowed or packed with debris and into or beyond a mine roadway adjacent to said pack-hole or seam, the chain or chains each having an upper and lower run passing at their ends about a drive sprocket and a return sprocket respectively and only being guided and supported at their ends, a sweeping means mounted on the chain or chains so as to be located at or near the roof of the pack-hole or worked out seam and so as to be traversable by the chain or chains between a debris collecting position and a debris packing or stowing position, means to anchor the drive and return sprockets so as to tension the chain or chains therebetween and means for constraining the movement of debris away from a pack as it is being formed in the pack-hole or worked out mineral seam.

The invention is particularly useful in coal mining by the longwall technique where hydraulically powered self-advancing roof supports are usually provided along the face with roadways driven at each end of the face and the packs built with debris extracted from the ripping lip of each roadway.

The apparatus preferably comprises a catching hopper adapted to catch, and support above floor level, debris as is detached from the ripping lip of the roadway during the course of advancing the roadway, e.g., by shot-firing or a ripping machine and the sweeping means is adapted to extend into the hopper to obtain a load of pack-building debris. The anchoring means for each sprocket may comprise at least one hydraulic chock, and the drive sprocket may be driven by a hydraulic motor through a gearbox.

Thus a first load of debris may be swept by the apparatus from a loading position in the roadway and above floor level but below roof level of the pack-hole or worked out seam adjacent the roadway to fall to the floor to form part of the outer, roadway end of a pack in the pack-hole or worked out seam, but with a gap between the top of the first swept load and the roof of the pack-hole or worked out seam, while constraining the movement of debris away from the pack. Then a second load of debris may be swept over the top of the first load and through the gap to fall to the floor beyond the first load, and again leaving a gap at the top thereof, with successive loads swept through the successive gaps until the debris has been packed or stowed to the required length. The packing or stowing is then completed up to the roof by filling the gaps working from the inner end of the pack towards the outer, roadway

end by sweeping further loads of debris through the remaining gaps and over the tops of previous loads.

The apparatus may be attached to conventional roof supports extending along the mineral face preferably through substantially horizontally arranged hydraulic rams, which may be double-acting so that the roof supports are used as anchors, and the apparatus may be advanced in conjunction with the normal advance of the supports as the face advances. Of course, it is possible to provide separate staker props for this same anchoring purpose.

The sweeping means preferably projects unilaterally with respect to the chain or chains and it is usually desirable that it does not return debris on its return stroke towards the roadway. This may be achieved by constituting the sweeping means as a blade so mounted that it will in one position cause packing of the debris in one direction of movement of the chain or chains and in another position will cause packing in the other direction of movement of the chain or chains, the arrangement being such that during a driving, i.e., packing run, the blade bites into the debris while on its return run the relationship of the blade to the chain or chains is unchanged so that instead of sweeping back debris in the reverse direction, the blade rides itself out of the debris.

Thus, the chain or chains may be attached to each end of a back plate from which extends transversely to the direction of movement of the sweeping means a support arm carrying two spaced apart and downwardly directed brackets suitably apertured to receive a pivot pin, transversely to the direction of movement of the sweeping means, on which the blade is pivoted at its mid-length. With the blade provided, towards each end of its upper surface, with an apertured bracket, and with each side of the support arm also provided with an apertured bracket extending laterally from the arm, the arm brackets and blade brackets being located in adjacent parallel planes, the blade can be pivoted manually from a first inclined position in which the apertures in a blade bracket and its adjacent arm bracket are aligned for the insertion of a locking pin therethrough to a second inclined position, in which the locking pin passes through the aligned apertures in the other brackets, the selection of a direction of inclination depending upon the direction of packing.

The movement of the debris away from the pack may be constrained by a pack retaining shield adapted to form the face side wall of the pack thereby preventing pack building materials from falling e.g. into the rear ends of any powered supports, and enabling a solid pack to be achieved. The shield may be constructed from a number of separate plates, hinged together at their abutting edges (which are vertical when considering a substantially horizontal mineral seam), the number of plates employed being dependent upon the pack length required. The plates are self-supporting and the plate (if a pack is required only on one side of the roadway) or plates (if packs are required on both sides of the roadway) adjacent the hopper is or are attached thereto.

With one of the sprockets located in the roadway, the hopper may be curved upwardly in the area adjacent the anchoring means of that sprocket in order to stand clear of such anchoring means. However, with no sprocket in the roadway, the hopper can extend, at

constant height, right across the roadway. Thus, in the first case access to the hopper by the sweeping means is provided at one side only of the hopper, which in the second case it is provided at both sides of the hopper. To assist the sweeping means entering the hopper, the latter may be curved downwardly, to accommodate any lowering of the sweeping means from the roof level due to sag in the chain.

Such apparatus readily accommodates, and is unaffected by, unevenness of the roof of the pack-hole or worked out seam, and the apparatus may be satisfactorily installed at a main gate.

The invention will now be described in greater detail, by way of example with reference to the building of packs adjacent a mine roadway with reference to the accompanying drawings in which:

FIG. 1 is a sectional view of the apparatus according to the invention installed at one end of a longwall mineral face;

FIG. 2 is a plan view of FIG. 1 and additionally includes details of conventional roof supports;

FIG. 3 is a view in the direction of arrow A of FIG. 2;

FIG. 4 is a section on the line IV—IV of FIG. 2;

FIG. 5 is a section on the line v—V of FIG. 2;

FIG. 6 is a front elevation of the sweeping means;

FIG. 7 is a plan view of FIG. 6; and,

FIG. 8 is an end elevation of FIG. 6.

In FIGS. 1 to 5 a mine roof is indicated at 1, a floor at 2, a mineral face at 3, a pack hole in the goaf area at 4, a roadway at 5, a face end at 6 and a ripping lip at 7. Along the entire length of the mineral face 3 are disposed, in the conventional manner, a plurality of hydraulically powered advancing roof supports 8, as far as the vicinity of the roadway 5 where three support means 9 are located, with further roof supports 10 located beyond the roadway 5.

In the conventional manner, some of the force on the arches (not shown) that are erected as the roadway advances by removal of the ripping lip 7 is relieved, and the problem of disposal of at least some, if not all, of the debris removed from the ripping lip 7 is overcome, by the building of packs to one or both sides of the roadway 5. In FIG. 2 packs are built to both sides of the roadway 5 and these are a face side pack 11 and a rib side pack 12, and the apparatus of the invention is concerned with the building of these packs.

Accordingly a chain 13 extends along the length of the face side pack 11 across the roadway 5 and beyond it to extend the length of the rib side pack 12, the chain being located near the roof 1 and carrying a sweeping means 14. The chain 13 passes around a drive sprocket 15 located beyond the end of the face side pack 11 remote from the roadway 5 that is driven by a hydraulic motor and gearbox unit 16 while towards the end of the rib side pack 12, remote from the roadway 5, the chain passes around a return sprocket 17, the position of which is adjustable to tension the chain 13 by a hydraulic piston and cylinder unit 18.

The sprocket 15 and motor and gearbox unit 16 are attached to a vertically arranged end plate 19 which is hinged at 20 to an intermediate plate 21 in turn hinged at 22 to an end plate 23, in turn hinged at 24 to the framework of a catching hopper and platform unit indicated generally at 25, the plates 19, 21 and 23 constituting a pack retaining shield extending along the length of the face side pack 11 for constraining the

movement of the debris away from the pack. Similarly a pack retaining shield for the rib side pack 12 is constituted by an end plate 26, carrying the return sprocket 17 and ram 18, hinged at 27 to another end plate 28 hinged at 29 to the framework of the unit 25. At intervals along the face side of the shields are provided vertically arranged hydraulic anchor chocks 30, each attached to a single acting hydraulic advancing piston and cylinder unit 31 adapted to be attached to an adjacent roof support 8 or 10 and to employ that support as an anchor point for advancing the shields, drive sprocket 15 etc. The catching hopper and platform unit 25 is provided with advancing piston and cylinder units 32, one to each side, and these are respectively attached to an adjacent roof support 8 and 10 to advance the unit 25.

The unit 25 comprises a hopper 33 located beneath the ripping lip 7 that is being removed at a rate dependent upon the advance of the mineral face 3, the hopper being adapted to catch the debris as it falls from the ripping lip, while the unit also includes a platform 34 for personnel to attend to the ripping lip removal, e.g., by shot-firing. A platform extension 35 is shown on which may be located, e.g., a drilling rig to drill bore holes for the shot or alternatively a cutting head to remove the ripping lip 7 mechanically.

The unit 25 is adjustable in position by a pair of hydraulic piston and cylinder units 36 which raise or lower the hopper 33 by pivoting the latter about two spaced apart pivot pins 33A to allow, with the hopper in its uppermost position, the transport of items of equipment etc., to or from the mineral face area to proceed unhindered. The hopper 33 is open-ended and has a front wall 37 and an inclined rear wall 38 and beneath each open-end is provided a sloping plate 39 that is manually adjustable in position about a pin 40 to encourage debris that is being swept from the hopper 33 towards the pack areas into those areas rather than into the area of the roadway 5, the plates 39 being adjustable until they are inclined generally vertically downwardly to allow the removal of the unit 25 along the roadway after the restriction in width thereof by the insertion of conventional arches, which of course are inserted as soon as possible and as close as possible behind the unit 25.

In FIGS. 6 to 8 are shown details of the sweeping means 14 and this comprises a back plate 41 to each end of which the chain 13 is attached in one of two holes 42 provided for the purpose. A support arm 43 extends from the plate 41 towards the pack hole and carries two spaced apart brackets 44 apertured to receive a pivot pin 45 on which an inclined blade 46 is pivotable about its mid-length. The blade 46 is provided at its uppermost surface with two apertured brackets 47, one disposed to each side of the pivot pin 45, these brackets being in the same vertical plane as two further apertured brackets 48 located one to each side of the support arm 43. Depending on the direction of packing required, i.e., the direction of the working stroke of the chain and blade, the latter is moved so that the apertures in a blade bracket 47 and an adjacent arm bracket 48 are aligned and a locking pin 49 is then inserted through the aligned apertures, to fix the inclined position of the blade 46.

The apparatus is used as follows. Debris removed from the ripping lip 7 is caught in the hopper 33 and a first load of debris is swept from this loading position,

by actuating and motor ad gearbox unit 16, into the pack-hole to begin the formation of the pack 11, the debris falling to the floor 2 and a gap remaining at the top of the pack for the return of the blade by reversing the motor and gearbox unit 16. This procedure is repeated with subsequent loads of debris swept over the top of the first load and through the gap to fall on to the floor beyond the first load until the pack has been built to the required length. Then, it only remains necessary to complete the pack by filling in the gap left for the return of the blade by sweeping further loads of debris along the gap and over the tops of previous loads. During reverse driving of the blade, the fixed angle of the latter has the effect of riding the blade upwardly out of the debris to avoid any substantial amount of debris being swept back in the reverse direction.

Thus, packing is commenced from the roadway side of the pack hole and extends away from the roadway until a pack of the desired length has been built while the gap remaining at the top of the pack is filled in to complete the pack by building from the inner end of the pack towards the roadway.

When this has been achieved for the pack 11 the blade position is reversed so that the other brackets 47 and 48 of the blade and support arm respectively, are brought into use. When the pack 12 has been built the apparatus is ready for advancing by an amount depending upon the width of the hopper 33 and hence the length of the blade until the position is again as shown in FIG. 2. The advancing of the apparatus is achieved by retracting the anchor chocks 30 and then actuating the piston and cylinder units 31 and 32 which employ the roof supports 8 and 10 as anchors, the roof supports 8 and 10 of course being advanced as the face 3 advances, irrespective of the position of the packing apparatus of the invention.

What I claim is:

1. An apparatus for packing the debris removed from an advancing mine roadway having right and left sides into at least one elongated pack-hole adjacent the roadway and directed generally perpendicular to the roadway comprising:

1. a rotary drive element and a rotary return element, the drive and return elements being separated by approximately the length of the pack-hole and at least part of the roadway;

2. motor means for driving the rotary drive element;

3. endless means having an upper and a lower run passing about the rotary drive element and the rotary return element, whereby the endless means extends over the length of the pack-hole and at least part of the roadway;

4. a sweeping means carried by the endless means and located near the roof of the pack-hole so as to be traversible by the motor means between a debris collecting position within the roadway and a debris packing position within the pack-hole;

5. means for tensioning the endless means between the rotary drive and return elements; and

6. means for constraining packed debris from moving in the direction of the roadway advancement.

2. The apparatus as in claim 1 wherein said endless means is a chain and said rotary drive and return elements are sprockets which engage the chain.

3. The apparatus as in claim 2, additionally comprising a catching hopper positioned within the roadway

adapted to catch the debris removed from the roadway and wherein the sweeping means may be positioned in the catching hopper for collecting debris from the hopper.

5. The apparatus as in claim 2, in combination with anchoring means for supporting the drive and return sprockets at substantially the same height and wherein said anchoring means includes a hydraulic chock.

10. The apparatus as claimed in claim 2, wherein the motor means comprises a hydraulic motor and a gear box.

6. The apparatus as claimed in claim 2, wherein said tensioning means comprises a first hydraulic ram for pulling at least one of the rotary drive elements.

15. The apparatus as claimed in claim 4, in combination with a roof support and wherein said anchoring means includes a second hydraulic ram for coupling the hydraulic chock to the roof support.

8. The apparatus as claimed in claim 7, wherein the second hydraulic ram is double acting.

9. The apparatus as claimed in claim 2, wherein the sweeping means projects unilaterally with respect to the chain.

20. The apparatus as claimed in claim 2, wherein the sweeping means comprises a blade having first and second inclined positions, the first position for packing on the right side of the roadway and the second position for packing on the left side of the roadway.

25. The apparatus as claimed in claim 10, wherein the sweeping means additionally comprises a back plate, a support arm having two sides, the support arm being connected to the back plate, a pair of apertured spaced apart brackets projecting from the sides of the support arm, a pair of apertured brackets carried by the opposite side of the inclined blade, and a pivot pin passing through one apertured support arm bracket and one apertured blade bracket.

30. The apparatus as claimed in claim 11 wherein the debris constraining means comprises a retaining shield means.

12. The apparatus as claimed in claim 11 wherein the debris constraining means comprises a retaining shield means.

13. The apparatus of claim 12, wherein the shield means comprises a plurality of edge abutting plates which are hinged together at their edges.

35. The apparatus of claim 13, wherein the shield means spans the length of the pack-hole and abuts the hopper, and wherein a plurality of plates of the shield means are self-supporting and wherein the plate of the shield means adjacent the hopper is supported by a self-supporting plate of the shield means.

14. The apparatus of claim 13, including anchoring means for anchoring one of the sprockets in the roadway and wherein the hopper is curved upwardly on a side facing the anchoring means in order to stand clear of the anchoring means.

15. The apparatus of claim 3, including anchoring means for anchoring one of the sprockets in the roadway and wherein the hopper is curved upwardly on a side facing the anchoring means in order to stand clear of the anchoring means.

16. The apparatus of claim 3, wherein the hopper has a side curved downwardly to assist the sweeping means entering the hopper.

17. The apparatus of claim 16, wherein the hopper has two sides curved downwardly to permit the entrance of the sweeping means from either of the two sides.

18. The apparatus of claim 3, including anchoring means for anchoring the sprockets at the same height at the right and left sides of the roadway, whereby the chain extends at a substantially constant height across the roadway.

19. The apparatus of claim 3, including a piston and cylinder unit on each side of the hopper, and roof supports, the piston and cylinder units being attached to the roof supports.

20. The apparatus of claim 10, wherein said chain tensioning means comprises a first hydraulic ram.

21. The apparatus of claim 20 in combination with the anchoring means for supporting the drive and re-

turn sprockets at the same height.

22. The apparatus of claim 20, wherein said anchoring means includes a hydraulic chock and a second hydraulic ram directed in the direction of the roadway.

23. The apparatus of claim 22, wherein the drive and return sprockets are anchored at substantially the same height.
